UNITED STATES PATENT OFFICE.

ALTON E. GILBERT, OF TULSA, OKLAHOMA.

ROD-PULLING MACHINE.

1,249,947.

Specification of Letters Patent. Patented Dec. 11, 1917.

Application filed March 20, 1917. Serial No. 156,116.

To all whom it may concern:

Be it known that I, ALTON E. GILBERT, a citizen of the United States, and a resident of Tulsa, in the county of Tulsa and State 5 of Oklahoma, have invented a certain new and useful Improvement in Rod-Pulling Machines, of which the following is a specification.

My present invention relates generally to 10 rod pulling machines, and particularly to a machine applicable for the purpose of withdrawing the sucker rod from drilled wells, and consists generally in a pair of sucker rod clamping members arranged one 15 above the other in practice, the lower rod clamping member being mounted in connection with a frame engaged with and supported by the well casing, and the upper rod clamping member being suspended from 20 a cross bar, the latter of which may be hung onto a jack beam and the like for raising and lowering the same.

The objects of my present improvement include the provision of certain novel constructions and arrangement of parts permitting of ready disengagement thereof for purposes of repair and substitution, as well as to bring about more effective efficient results in use, and the provision as well of 25 means in connection with the lower rod clamping member whereby the latter may be utilized as a brake for safely and effectively lowering the sucker rod into the well after the necessary or desired repairs have 30 been made thereto, or to the well casing.

Referring now to the accompanying drawings in which my invention is illustrated, and which form a part of this specification:

40 Figure 1 is a front elevation illustrating my improvements in operative position;

Fig. 2 is a side elevation thereof;

Fig. 3 is a horizontal section taken substantially on line 3—3 of Fig. 1;

45 Fig. 4 is a vertical sectional view taken substantially on line 4—4 of Fig. 3;

Fig. 5 is a detail perspective view of one of the detachably supported uprights; and

Fig. 6 is a detail perspective view of one 50 of the rod engaging members for utilization with the lower clamping member in lowering a sucker rod into a well.

Referring now to these figures, and particularly to Figs. 1 and 2, I have shown a 55 sucker rod at A extending into a well, the

casing of which is indicated at B, and I have shown in connection with the sucker rod A the upper and lower clamps 10 and 11 therefor, each of these clamps consisting of aligned clamping members 12 and 13, the inner adjacent ends of which have intermediate recesses or cut out portions 14, as plainly seen by reference to Fig. 3, in which the clamping blocks 15 are disposed, these clamping blocks having vertical grooves 60 65 preferably provided with teeth and of somewhat the shape of the contour of the sucker rod A.

The clamping blocks 15 have transverse openings 17 which align with transverse 70 openings of the clamping arms 12 and 13, for the reception of transverse pins 18, upon which the blocks are swiveled so as to adjust the same to any irregularities in the sucker rod and firmly and uniformly 75 clamp the same as the arms 12 and 13 assume horizontal positions.

The inner ends of the clamping arms 12 and 13 are also provided with extensions at opposite sides of their cut away portions 14, 80 which extensions are apertured for the reception of pintles 19 to form hinges connecting the inner adjacent ends of the clamping arms, constituting the joints thereof, and the outer ends of which pintles 85 19 normally project beyond the sides of the clamping arms, as plainly seen by reference to Fig. 3, to receive the intermediate coils 20 of springs 21, the arms of which extend outwardly beyond the sides of the clamping 90 arms 12 and 13 and are anchored at their outer ends to these clamping arms, so as to normally urge the latter to horizontal positions and thus hasten their clamping action in use.

The clamping arms 12 and 13 of the upper clamp 10 are suspended from a cross bar 22, the latter of which is adapted for disposal over, or to be hung onto, a jack piece in the power operation of the device, 100 this cross bar having hooks 23 at its opposite ends receiving the upper apertured ends 24 of suspension members 25, the latter of which have their lower apertured ends extending into the bifurcated outer ends of 105 the clamping arms 12 and 13 for the reception of connecting pins 26, forming a pivotal connection and permitting of ready detachment of the arms 12 and 13 when desired.

The clamping arms 12 and 13 of the lower clamping member have their bifurcated outer ends receiving the upper reduced ends 27 of a pair of supporting uprights 28, 5 the reduced extensions 27 of which have slotted openings 29, as seen in Fig. 5, receiving pins 30 connecting the same to the clamping arms 12 and 13. The lower ends of the uprights 28 have reduced squared extensions 31 which interfit conformable recesses in the outer adjoining faces of a pair of pipe clamping cross arms 32, the latter of which are secured in face to face relation by means of bolts 33 and have inner curved 10 portions for clamping engagement with the upper end of the well casing B, as clearly seen by reference to Figs. 1, 2, and 4.

My invention furthermore provides a lever 35 as seen in Figs. 1, 2, and 3, having 20 apertures at its head end in angular relation to one another, in order to receive the projecting end of one of the hinge pintles of the lower rod clamp 11, and the adjacent projecting end of one of the transverse pins 25 18 of a clamping block 15, whereby closing movement of the clamping arms 12 and 13 of the lower clamp 11 may be controlled manually in lowering a sucker rod A into a well after the latter or the sucker rod has 30 been repaired, as desired, interchangeable clamping blocks 15^a, one of which is seen in Fig. 6, being provided with the clamping blocks 15 in connection with my improvements, having vertical grooves 16^a with 35 smooth surfaces so as to frictionally engage the surface of the sucker rod A in lowering the same into the well instead of a biting grip into the material thereof, as provided

for in connection with the toothed grooves of the blocks 15 first above described.

It is obvious therefore that my invention provides an arrangement of the present type wherein the parts may be readily disengaged for purposes of repair and substitution, and are of such nature as to bring about effective and efficient operation and results in their use. It is further obvious that my invention provides an arrangement which, by means of slight change, for instance, the substitution of blocks 15^a for 50 the blocks 15 of the lower clamp 11, may be utilized to manually control the lowering of a sucker rod into a well, effectively and efficiently and without danger of breakage.

I claim:

In a rod pulling machine, a rod engaging clamp consisting of a pair of clamping members pivotally supported at their outer ends and having extensions at their inner adjacent ends interfitting one another and apertured pins extending through the apertures of the said interfitting extensions to form hinges connecting the inner adjacent ends of the clamping members, the outer ends of which pins project beyond the respective sides of the clamping members, and springs having intermediate coils mounted on the projecting ends of said pins and having their outer ends anchored to the sides of the clamping arms, for the purpose described.

ALTON E. GILBERT.
